UNITED STATES PATENT OFFICE

ROY W. BROWN, OF AKRON, OHIO, ASSIGNOR TO THE FIRESTONE TIRE AND RUBBER COMPANY, OF AKRON, OHIO, A CORPORATION OF OHIO

JACKETED MOLD

Application filed March 16, 1928. Serial No. 262,134.

This invention is to provide a jacketed molds such as are used for vulcanizing tires.

The general purpose of the invention is to provide a jacketed mold construction in which the pressure of a fluid curing medium 5 is effectively used to force the molding surfaces together.

More particularly, the invention has for its object the provision of a sectional mold, the sections of which are arranged to be held together by suitable means and at least one of which sections is jacketed, a wall or walls of the jacket being flexible whereby the molding surface of said section is urged against the other mold section by pressure of a fluid 15 medium such as the curing medium.

The foregoing and other objects are obtained by the construction illustrated in the accompanying drawings and described below. 20 It is to be understood that the invention is not limited to the specific form thereof disclosed herein.

Of the accompanying drawings:

Figure 1 is a plan view of a jacketed vulcanizing mold embodying the principles of 25 the invention;

Figure 2 is a transverse vertical section thereof;

Figure 3 is an enlarged scale sectional de- 30 tail taken on the line 3—3 of Figure 1;

Figure 4 is a diagrammatical elevation of a layout; and

Figure 5 is an end view thereof.

Referring to the drawings by reference numerals, 10 represents the lower casing or wall of a steam jacket positioned about a mold half 11. The upper half of the mold consists of an inner mold wall 12 having a heating medium chamber formed thereabout 35 by jacket wall 13. Wall 10 is provided with a circumferential flange 14 carrying annular locking ring 15 for uniting the upper and lower sections of the mold, the upper portion of the locking ring being provided with a 40 series of arcuate lugs 16 adapted to pass be-

tween arcuate lugs 17 on the upper mold half. When the upper half or lid of the mold is assembled with the lower half, the mold parts may then be locked together by swinging lever 18 which turns pinion 19 meshing with a rack 20 formed underneath the locking ring, whereupon the lugs 16 and 17 will overlap to lock the parts together. Inlet and outlet pipes 21 and 22, and 23 and 24, respectively, are connected to the upper and lower heating medium chambers for the circulation of the medium therethrough, the upper conduit being provided with flexible connections 25, 26 to permit flexing thereof when the mold lid is raised.

The lower half of the mold wall is constructed to have a slight vertical movement relatively to the upper mold half in order that the pressure of the heating medium in the lower chamber of the jacket may force 55 the lower mold half tightly into engagement with the upper section. This construction permits the perfect formation of the tread design on the tire and at the same time prevents the formation of the fin of rubber about the 60 periphery of the tire.

Independent movability of the lower mold half 11 is obtained by forming a thin bellows portion 27 in the web which connects mold half 11 to the jacket 10, movement of 75 the mold half being limited by cooperating stop members 28 formed on the adjacent portions 10 and 11. The space between the periphery of mold half 10 and the jacket 11 is sealed by a flexible diaphragm 29 backed up 80 by segmental pressure resisting plates 30 held in place by clamping rings.

When the fluid pressure of the heating medium is built up in the lower chamber the lower mold half is forcibly urged against the upper mold half to make a tight joint between the same at the tread portion of the tire. A convenient layout for operating the type of vulcanizer disclosed herein is illustrated in Figures 4 and 5, a line of the molds 85

being placed side by side. A lifting jack 32 of any suitable construction is mounted to roll along a track 33 adjacent the molds for selectively raising the lids of the molds by means of hydraulic pressure operating within a double acting cylinder 34.

The operation of the apparatus will be readily understood from the description above and in brief is accomplished by placing the green tire casing 35 having the customary air bag 36 therein within the lower half of the tire mold. The lid is then locked in place by swinging lever 18. The heating medium such as hot water or steam at vulcanizing temperatures is next admitted to the jackets to effect the cure and to force the lower mold half tightly against the upper mold cavity, suitable air bag connections with valve stem 37 being also made. After the cure has been completed, the locking ring 15 is rotated to release the upper mold half which is then raised by the jack to permit the removal of the tire from the mold.

Modifications of the structure herein disclosed may be resorted to without departing from the spirit of the invention or the scope thereof as defined by the appended claims.

What is claimed is:

1. Vulcanizing apparatus comprising a pair of cooperating jacketed mold sections having fluid heating medium chambers therein, and flexible walls provided about the chamber of one of said mold sections to permit the pressure of the heating medium introduced therein to force the latter mold section relatively towards the other mold section.

2. Vulcanizing apparatus comprising a pair of cooperating jacketed mold sections having fluid heating medium chambers therein, means for holding said mold sections substantially together, and a bellows wall defining the chamber in one section whereby the pressure of the heating medium introduced therein forces the mold sections relatively together.

3. Vulcanizing apparatus comprising a pair of opposed cooperating jacketed mold sections having fluid heating medium chambers therein, a bellows wall, and a flexible diaphragm, respectively, on opposite sides of the cavity in one mold section and defining the chamber therein, whereby the pressure of the heating medium introduced therein forces the mold cavity relatively towards the other mold section.

4. Vulcanizing apparatus comprising a pair of jacket members adapted to be clamped together, a mold section fixed to one of said jacket members to define a heating medium chamber therein, a mold section connected to the other jacket member to define a heating medium chamber therein, a flexible wall connecting one of said mold sections to its jacket member whereby the pressure of a fluid heating medium introduced in the last mentioned

chamber forces said mold section toward the other mold section.

5. Vulcanizing apparatus comprising cooperating mold parts adapted to be clamped together, one of said parts being jacketed to define a heating medium chamber therein, said jacketed member having a flexible wall whereby the pressure of a fluid heating element introduced in the chamber forces said part toward the other mold part.

ROY W. BROWN.
